UNITED STATES PATENT OFFICE

JOSEPH P. STREET, OF CHATTANOOGA, TENNESSEE

CABLEWAY CARRIAGE

Application filed January 5, 1929. Serial No. 330,660.

This invention relates to aerial cableways and more especially to carriages for use in connection therewith, these carriages being of the type adapted to employ carriers used for supporting the running lines of the cableways. The invention is more especially an improvement upon the structure disclosed in Patent Number 1,520,780 issued to me on December 30, 1924.

In structures of the type referred to it is the practice to utilize carriers for supporting the running lines at substantially predetermined distances apart, the carriage being provided with a means for successively picking up these carriers while moving in one direction and for successively delivering the carriers to the main or supporting cable when the carriage travels in the opposite direction. While a structure of the type disclosed in my patent hereinbefore referred to has operated efficiently, it has been found that, when the carriage is travelling at a high speed and it is desired at the same time to pick up the carriers, said carriers have, at times, bounced back from the horn after being received thereby. It is an object of the present invention to provide a means for retaining the carriers on the horn of the carriage after they have been received thereby and until it is desired to deliver them therefrom.

A further object is to provide simple and efficient means for resetting the mechanism should any of the parts slip so as not to properly distribute the carriers.

A still further object is to provide a means for reducing to the minimum the wear on the horn forming a part of the carriage.

With the foregoing and other objects in view which will appear as the description proceeds the invention resides in the combination and arrangement of parts and in the details of construction hereinafter described and claimed it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a side elevation of a portion of a carriage having the present improvements, a part being shown in section.

Figure 1^a is a side elevation of the remaining portion of the carriage. 55

Figure 2 is an enlarged section on line 2—2, Figure 1.

Figure 3 is an enlarged section on line 3—3, Figure 1.

Figure 4 is a section on line 4—4, Figure 2. 60

Referring to the figures by characters of reference 1 designates a portion of the side plates of the carriage, these side plates cooperating to constitute the main portion or body of the carriage. They are adapted to be supported by any desired number of sheaves 2 and an additional or drive sheave 3 all of which are mounted to travel on the main supporting rope or cable A. An in-haul line 4 is connected to one end of the body 1 of the carriage while an out-haul line 5 is adapted to be connected to the other end of the body of the carriage. Thus the carriage can be moved back and forth along the main supporting rope or cable A in the same manner as disclosed in my patent hereinbefore mentioned. 70 75

The sheave 3 and adjacent sheave 2 are mounted between truck plates 6 and these plates are attached to the side plates 1 of 80 the body for supporting them.

The sheave 3 is keyed or otherwise fastened to its shaft 7 and this shaft has a gear 8 which meshes with a gear 9 carried by a sleeve 10. On this sleeve is journaled the hub 11 of a friction clutch member 12 adapted to be engaged by another friction clutch member 13 which is keyed or otherwise secured to a shaft 14 journaled in a bearing bracket 15 extending laterally from the rear forked end portion 16 of an elongated horn 17. This forked portion of the horn is pivoted on the shaft 7 and is extended backwardly therefrom past the adjacent sheave 2. Links 18 connect these back portions of the 90 forked end of the horn to levers 19 fulcrumed at 20 between the plates 1 and carrying counterbalancing weights 21. Each lever is adapted to move along an arcuate guide strip carried by one of the plates 1. Load sheaves 23 95

are mounted between the plates 1 and guide sheaves 24 are mounted between the plates 1 adjacent their upper edges for engaging the main supporting rope or cable A.

5 The front or free end of the horn 17 has a pick-up head 25 the upper edge of which is inclined downwardly from a retaining shoulder 26. A crosshead 27 is slidably mounted on the horn and extended laterally therefrom 10 to provide bearings 28, 29 and 30. In the bearings 28 and 29 is secured a feed nut 31. The shaft 14 is screw-threaded for the greater portion of its length, as shown at 32 and this threaded portion extends through and engages the nut 31. A longitudinal keyway 33 is formed in the threaded portion of the shaft 14 and provides a seat for a key or feather 34 extending inwardly from a worm 35 in the form of a sleeve held between the bearings 29 15 and 30 and adapted to rotate with the shaft 14. As shown particularly in Figure 1 the worm 35 has an annular groove at each end into which the spiral groove defined by the worm opens at both ends.

25 The free end portion of the shaft 14 has a nut 36 mounted thereon and constituting an abutment for one end of a coiled spring 37 extended toward the crosshead 27. A collar 38 is adjustably mounted on the shaft 14 30 between the bearings 15 and 30 and has a coiled spring 39 extending therefrom toward the bearing 30.

35 A segmental gear 40 is journaled on the crosshead and has an arm 41 extending therefrom, this arm being provided with a spring pressed pin 42 adapted to ride in the groove of the worm 35. A stud 43 is extended downwardly from the arm 41 between centering plungers 44 which are slidable within sleeves 40 45 held by the bearings 29 and 30. In these sleeves are coiled springs 46 which tend to thrust the plungers toward each other so as to hold the stud 43 normally centered between the bearings 29 and 30. These springs are 45 adapted to be adjusted by means of screw plugs 47.

50 A mutilated gear 48 is journaled on the crosshead and meshes with the segmental gear 40. This mutilated gear has a wrist pin 49 engaged by a link 50 which, in turn, is pivotally connected to a distributing plunger 51 slidable longitudinally of the crosshead and having a depending head 52. This plunger is slidable within guides 53 on the crosshead and one of these guides is extended upwardly as shown at 54 to provide a support for an elongated channeled strip 55 located above the horn 17 and pivotally mounted adjacent one end, as shown at 56, in a bracket 57 carried by the rear portion of the horn.

55 A bracket 58 is connected to and extends upwardly from the distributing plunger 51 and is provided with an opening 59 through 60 which the channeled strip 55 extends loosely.

Jaws 60 are pivotally connected to the bracket 58 and a rod 61 is extended transversely through them, there being springs 62 mounted on the end portions of the rod. Each spring bears at one end against a head or nut 63 on the end of the rod and at its other end against one of the jaws. Thus the free ends of the jaws are pressed normally toward each other where they will frictionally engage opposite faces of an annular rod 64 extending longitudinally of the channeled strip 55 and mounted in guides 65 provided therefor.

70 The free end of the strip 55 is located above the upper inclined face of the head 25 of horn 17 and has a pawl 66 pivotally connected thereto. An arm 67 is extended from this pawl and, as shown particularly in Figure 1, is normally in the path of the rod 64. Obviously, when the rod 64 is drawn to the right in Figure 1 so as to be pulled away from the arm 67, the pawl 66 will hang downwardly over the head 25 so as to retain on the horn any members engaged thereby. However, when rod 64 is thrust to the left 75 in Figure 1, it will come against the arm 67 and raise the pawl 66 as shown in said figure, so as to release any objects held by the horn.

80 A spring 68 is interposed between the head 52 of the distributing plunger 51 and the adjacent guide 53 so that said head is thus normally thrust away from the guide.

85 Depending from the crosshead 27 are spaced bumpers 69 which straddle the main supporting rope or cable A. Links 70 are pivotally connected to the lower portions of the bumpers and extend between the plates 1 of the body of the carriage where they are pivotally connected to the lower ends of levers 71 fulcrumed on and depending from the portion 16. At intermediate points these levers 71 are connected by links 72 to levers 73 which are fulcrumed at their lower ends in a frame 74 supported by the rear portion 16 of the horn.

90 The upper ends of the levers 73 are connected by links 75 to the crosshead 27. The links 75 with the other levers and links 71, 72 and 73 act to hold the lower portions of the bumpers against swinging relative to the horn 17 and binding thereon. Instead, when the lower portions of the horn are subjected to thrust, said thrust will be transmitted through the links 70 to the levers 71 which, in turn, will pull through the links 72 upon levers 73. These levers will pull through the links 75 upon the upper portion of the crosshead. Consequently the thrust against the lower portions of the bumpers will be 95 equalized at the top of the crosshead and danger of said crosshead tilting and binding on the horn so as to wear it, is eliminated.

100 A plurality of fall rope carriers has been indicated at 76 and are adapted, as ordinary

ly, to be distributed at substantially regular distances along the main supporting rope or cable A. When it is desired to pick up these carriers the carriage is pulled along the cable or rope A by means of the line 4. During the first portion of this movement of the carriage sheave 3 will transmit motion through the gears and friction clutch to the shaft 14, thereby causing the worm 35 to revolve with the shaft and at the same time feed the crosshead 27 along the threaded portion of the shaft 14 away from the nut or collar 36.

During the first portion of the foregoing movement the pin 42 will be shifted by the worm so as to actuate the gears 40 and 48 and cause the link 50 to thrust against plunger 51 and move the head 52 toward the guide 53, thereby to compress spring 58 and move the head 52 away from the shoulder 26. This will provide sufficient clearance to receive the supporting wheel 77 of the first fall rope carrier 76. At the same time this movement of plunger 51 will pull the bracket 58 toward the pivot 56 of the channeled strip 55 and, consequently, the jaws 60, which grip the rod 64, will pull said rod away from the arm 67 and allow the pawl 66 to drop down to retaining position from the position shown in full lines in Figure 1. This retaining position of the pawl has been indicated by broken lines in Figure 1. With the parts thus located the carriage, as it is moved along the main rope or cable A will pick up the fall rope carriers successively, the first carrier riding upwardly on the inclined upper edge of the head 25 past the pawl 66 and into the space between the shoulder 26 and the head 52. As the carriage continues to move forwardly the head 52 will be drawn farther back by the crosshead 27 thence upwardly by the threaded shaft 14. Thus room is provided to receive the wheel 77 of the second fall rope carrier. By the time the crosshead reaches the limit of its sliding movement along the horn 17 all of the fall rope carriers will have been picked up and be supported by the horn as shown in Figure 1.

When it is desired to distribute the carriers over the main supporting rope or cable A, the movement of the carriage is reversed by pulling through the line 5. During the first portion of this return movement the pin 42 is shifted by the worm 35 into the annular groove at the other end of said worm. This will cause motion to be transmitted by the gears 40 and 48 through the link 50 to the plunger 51 so that head 52 will be thrust against the wheel 77 of the adjacent fall rope carrier. During the first portion of this movement the rod 64, which is gripped by the jaws 60, will thrust against the arms 67 and raise the pawl from the dotted position shown in Figure 1 to the full line position. Immediately following this the head

52, thrusting against the wheels 77 of the collective fall rope carriers, will push the wheels 77 of the first carrier over the shoulder 26 so that it will ride down along the inclined edge of head 25 on to the rope or cable A. This movement is of course set up by the travel of the crosshead 27 along the horn 17 through the action of the threaded portion of the shaft 24. The positions of the parts following the shifting of the rod 64 to lift the pawl and prior to the delivery of the first fall rope carrier, is shown in Figure 1. Following the delivery of the first fall rope carrier, the crosshead is gradually moved toward the head 25 until the head 52 pushes another fall rope carrier over the head 25 and on to the cable or rope A. During this time the jaws 60 slide along the engaged rods 64. Thus the fall rope carriers will be delivered at regular intervals on to the main supporting rope or cable after which the carrier can be reversed and the operation will be repeated as already described. It might be added that, during the selecting of the fall rope carriers the jaws 60 slip along the rod 64 from one extreme position to the other and, at this time, is limited in its rearward sliding movement by one end thereof coming against a suitable stop provided therefor within the channeled strip 55. Such a stop has been shown for example by dotted lines at 78 in Figure 1.

It will be understood that, as the mechanism of this carrier is operated by the sheave 3 in engagement with the main supporting rope or cable A, there will be a slight slipping of the sheave on the cable during the rapid back and forth movement of the carriage. This slipping occurs when the carriage is not loaded. Each time the carriage travels in one direction a small amount of slippage is liable to occur and ultimately this slippage will amount to so much as to make an uneven distribution of the fall rope carriers along the main supporting rope or cable A. To correct this the carriage is caused to move along the supporting rope or cable A until the crosshead 27 has come into contact with the limit stop ordinarily provided and not shown in the drawings. This will result in one of the springs 37 or 39 coming against the adjacent bearing 28 or 30 and contracting while the shaft 14 is held against rotation. The friction clutch made up of the parts 12 and 13 permit of a slip drive between the sheave 3 and shaft 14 during this operation. In other words the carriage is caused to travel to the limit of its movement while the friction connection is slipping and when it reaches said limit the crosshead is in correct position on the horn 17 to begin the operation of collecting the fall rope carriers.

What is claimed is:

1. The combination with a track cable, and a carriage movable therealong including a sheave engaging and rotatable on the cable, of means movable with the carriage for supporting a plurality of fall rope carriers, a freely movable retaining pawl movable into and out of retaining position, said pawl being adapted to hold the fall rope carriers on the supporting means, and means operated by the rotation of the sheave for successively shifting the retaining pawl to release the fall rope carrier and delivering said carriers on to the cable from the supporting means.
2. The combination with a track cable, of a carriage movable therealong including a supporting sheave for engagement with the cable, means movable with the carriage for supporting a plurality of fall rope carriers, a freely movable retaining pawl supported adjacent to said supporting means and movable into and out of retaining position, said pawl being adapted to hold the fall rope carriers against jumping from the supporting means, means operated by the rotation of said sheave for shifting the retaining pawl to free the fall rope carriers and for successively delivering said carriers from said supporting means during the movement of the carriage along the cable in one direction, thereby to deposit the carriers at substantially regular intervals.
3. The combination with a supporting cable, of a carriage mounted thereon including a rotatable sheave, means movable with the carriage for supporting a plurality of fall rope carriers, a retaining element movable into and out of retaining position, said element being adapted to hold the fall rope carriers against displacement from the supporting means, ejecting mechanism operated by said sheave for delivering the carriers successively from the supporting means to distribute them at substantially regular intervals along the cable, and means operated by the ejecting mechanism for shifting the retaining element to releasing position in advance of the ejection of the fall rope carriers.
4. The combination with a supporting cable, of a carriage mounted thereon including a rotatable sheave, means movable with the carriage for supporting a plurality of fall rope carriers, a retaining element movable into and out of retaining position, said element being adapted to hold the carriers against displacement relative to the supporting means, ejecting mechanism operated by the sheave for delivering the carriers successively from the supporting means to distribute them at substantially regular intervals along the cable, and means including a slip connection for transmitting motion from the ejecting mechanism to the retaining element to shift said element and release the fall rope carriers in advance of the ejection thereof.
5. The combination with a supporting cable, of a carriage mounted thereon including a rotatable sheave, means movable with the carriage for supporting a plurality of fall rope carriers, a retaining element movable into and out of retaining position, said element being adapted to hold the carriers against displacement relative to the supporting means, ejecting mechanism operated by the sheave for delivering the carriers successively from the supporting means to distribute them at substantially regular intervals along the cable, and means actuated by the ejecting mechanism for shifting the retaining element to release the fall rope carriers in advance of the ejection thereof, said means including friction jaws movable with the ejecting mechanism and a push rod for engaging the retaining element to shift it to releasing position, said rod being frictionally and slidably engaged by the jaws for actuation thereby.
6. The combination with a track cable, of a carriage movable therealong and including a cable supporting sheave mounted for rotation, means movable with the carriage for supporting a plurality of fall rope carriers, ejecting mechanism movable relative to the supporting means and including a crosshead, a distributing plunger movable relative to the crosshead, means operated by the rotation of the sheave in one direction for successively shifting the distributing plunger relative to the crosshead and moving the crosshead relative to the supporting means, thereby to eject the carriers successively from the supporting means and deposit them on the cable, a retaining element movable into and out of retaining position, said element being adapted to hold the carriers against displacement from the supporting means, and means actuated by the distributing plunger for shifting the retaining element in advance of the ejection of the carriers, thereby to release said carriers for delivery from the supporting means.
7. The combination with a track cable, of a carriage movable therealong and including a rotatable sheave, a horn movable with the carriage for supporting fall rope carriers, a pick-up head at the free end of the horn, a crosshead supported by the horn, means operated by the sheave for moving the crosshead toward the head of the horn, a member supported above the horn, a retaining element movably connected to said member, for holding the fall rope carriers against displacement from the horn, and means actuated by the crosshead for shifting the retaining element to release the fall rope carriers prior to their ejection from the horn by the crosshead.
8. The combination with a track cable, of a carriage movable therealong and including a rotatable sheave, a horn movable with

- the carriage for supporting fall rope carriers, a pick-up head at the free end of the horn, a crosshead supported by the horn, means operated by the sheave for moving the crosshead toward the head of the horn, a member supported above the horn, a retaining element movably connected to said member, for holding the fall rope carriers against displacement from the horn, and means actuated by the crosshead for shifting the retaining element to release the fall rope carriers prior to their ejection from the horn by the crosshead, said means including a distributing plunger slidably mounted on the crosshead, means for shifting said plunger relative to the crosshead, at the beginning of movement of the crosshead in either direction, and a lost motion friction connection between said plunger and the retaining element.
9. The combination with a track cable, and a carriage movable therealong including a sheave, of means movable with the carriage for supporting a plurality of fall rope carriers, means operated by the rotation of the sheave for successively delivering the carriers on to the cable from the supporting means, a member connected to the carriage and extending over the supporting means, a pawl suspended therefrom for holding the carriers against displacement from the supporting means, a rod movable against and away from the pawl to shift the pawl out of and into position for retaining the fall rope carriers, and a lost motion friction connection between the delivering means and the rod.
10. The combination with a track cable, of a carriage movable therealong, a horn tiltably connected to and projecting beyond one end of the carriage, yielding means connected to the horn for holding it normally elevated at its free end, a crosshead movable along the horn, means operated by the movement of the carriage for shifting the crosshead relative to the horn, spaced bumpers depending from the crosshead, and thrust equalizing connections between the lower portions of the bumpers and the upper portion of the crosshead.
- 50 In testimony that I claim the foregoing as my own, I have hereto affixed my signature.

JOSEPH P. STREET.
